CONTINUOUS FASTENER

Harry E. Sipe, New York, N. Y.

Application October 6, 1933, Serial No. 692,479

8 Claims. (Cl. 24—205)

My invention relates to continuous fasteners and more particularly to such fasteners for closing the mouths of pocket books, tobacco pouches or the like.

5 The primary object of my invention is to provide a fastener of this type which is inexpensive to make and easy to operate. Furthermore, a tight closure which effectively prevents leakage is obtained.

10 Another object of my invention is to produce a continuous, air tight closure which does not require a slide for its operation, but can be opened by a pull in a transverse direction and closed by the normal contraction of the parts of the closure 15 after pulling in a longitudinal direction.

15 The invention in general comprises two parallel elastic strips having interlocking portions thereon. The strips can be separated by pulling them apart transversely while they may be again interlocked by longitudinal stretching. Preferably, 20 each strip is of rubber pre-formed to the desired shape and vulcanized to such shape. The form chosen is such that the parts always tend to assume the closed position and must be stretched 25 to release the closure. Each strip has lugs or projections thereon separated by sockets whose size is increased or shape so changed by separation or stretching of the strips as to permit the projections to escape from and reenter the sockets.

30 I prefer to form the projections of rubber as these rubber elements by their contact will form an air-tight seal. However, I may form the projections of metal, in which case the closure may still be operated in the same fashion.

35 Further objects and advantages of the invention will be understood more fully from the following description when taken in conjunction with the accompanying drawing which forms a part thereof.

40 In the drawing:

Fig. 1 shows in side elevation a bag to which my fastener is applied.

Fig. 2 is a top plan view of the fastener element in closed position.

45 Fig. 3 is a similar view showing the fastener in stretched condition as it is being closed.

Fig. 4 is a cross section on the line 4—4 of Fig. 2.

47 Figs. 5 and 6 are views similar to Figs. 2 and 3 of a modified form of fastener.

50 Figs. 7 and 8 are further views similar to Figs. 2 and 3 of still another form.

55 Fig. 1 shows a bag 2, for example a pocket book or tobacco pouch, having its upper edge closed by my fastener. The fastener comprises two parallel strips 4 of rubber or some other stretchable, and

preferably resilient, material. These strips are secured along the inner edges of the bag opening by an adhesive or in any other suitable manner. The ends 6 of the strips are preferably (but not necessarily) secured together by vulcanizing or 5 cementing to form pull tabs 16.

The strips 4 are shaped in the manner shown in Fig. 2, being folded into this form and then vulcanized so that they will always assume this shape when free. Each strip has projecting portions 8 separated by sockets or recesses 10, the sockets and projections being of course staggered on the opposed strips. The projections and sockets are substantially triangular, the bases of the projections and the outlets of the sockets being 15 smaller than the remaining parts. Obviously this interlocked arrangement will normally prevent separation of the two strips and will keep the bag closed. In effect, the sockets are the spaces between the projections and are of the same size 20 as the projections. The connecting portions 15 of the strip between the projections 8 are made in such a way as to be deformable to elongate the distance between projections. This will cause expansion of the recesses 10 to permit the projections of the opposite strip to enter and pass out. Preferably the connecting portions are normally set in a devious line so that when they are stretched into more nearly a straight line the strips as a whole will be elongated. Whenever 30 the terms "deformable" and "stretchable" are used herein they are intended to describe fastener strips of a size useful for the purposes set forth in this specification and to define the quality of substantial deformation or stretching by a usual 35 manual pulling force applied to such fastener strips.

At the center of each strip 4 is secured a pull 12. This pull is preferably hinged so as to lie flat against the bag when not in use, as shown in 40 Figs. 1 and 3.

In order to open the bag, the two pull tabs 12 are drawn apart. Because of the stretchable quality of the rubber strips, the projections near the centers of the strips will be compressed and 45 the sockets will therefore expand, thus releasing the two strips. This opening action will proceed progressively to the ends of the strips, and the whole mouth of the bag will be open. 50

To close the bag, the end portions 6 are grasped and drawn apart, causing the strips to assume the shape shown in Fig. 3. The projections are then within the sockets. When the ends are released, the sockets contract and lock the pro- 55

jections in closed position, taking again the form shown in Fig. 2.

In Figs. 5 and 6, the tongues or projections 8' and sockets 10' are of somewhat different shape, the tongues being of substantially uniform thickness but arranged at an acute angle to the longitudinal direction of the strips. The sockets, being the spaces between the projections, will slope in the same way.

10 This arrangement is opened and closed in exactly the same fashion as the form shown in Figs. 1 to 4. The angular interlocking tongues normally prevent separation, but tension applied to the pull members is enough to separate 15 the tongues and thus to open the fastener. To close the fastener the ends are pulled, drawing the parts to the position shown in Fig. 6, and then released.

10 Figs. 7 and 8 show a further form having 20 sockets 10" and projections 8" of the same general form as in Figs. 1 to 4. In this form, however, the construction is more solid, and might be stamped or otherwise cut from rubber. This modification operates in the manner previously 25 described.

While I have described my strips as composed of rubber, it is quite evident that they might be formed in some other manner. For example, the 30 projections may be formed of metal or other hard material secured together resiliently. The essential feature of the invention is the provision of sockets and tongues some of which can be deformed by a transverse pull so as to release the projections and by a longitudinal force 35 so as to permit the reentry of the projections. There are many obvious advantages, however, in forming the fastener entirely of rubber or some similar material.

It will be evident that the material of the bag 40 should be somewhat gathered or puckered at the point of attachment of the strip (as at 14) so as to permit the strip to expand. While I have described herein some embodiments of my invention, I wish it to be understood that I do 45 not intend to limit myself thereby except within the scope of the appended claims.

I claim:

1. A fastener comprising a pair of flexible strips each having uniformly spaced projections 50 thereon, connecting portions between said pro-

jections and recesses between the projections having a normal shape corresponding to the shape of the projections, the recesses and projections on the two strips being staggered and so shaped that they will interlock together when intermeshed, the connecting portions between said projections being deformable by a force applied longitudinally of the fastener to expand said recesses sufficiently to permit free entrance of said projections into said recesses. 10

2. A fastener comprising a pair of flexible strips each having uniformly shaped projections thereon, connecting portions between said projections and recesses between the projections having a normal shape corresponding to the 15 shape of the projections, the recesses and projections on the two strips being staggered and so shaped that they will interlock together when intermeshed, each connecting portion being normally set in a devous line and being deformable 20 into more nearly a straight line by force applied longitudinally of the fastener, whereby the recesses are expanded sufficiently to permit entrance of said projections into said recesses.

3. A fastener according to claim 1 wherein the material of the strips is rubber and wherein each of said connecting portions is normally set in a devous line whereby a straight longitudinal pull will deform said wall into a straight line to expand said recess. 25

4. The combination set forth in claim 1 wherein pull tabs are provided at the ends of the strips for exerting a longitudinal force on the strips to close the fastener.

5. The combination defined in claim 1 where- 35 in pull tabs are provided at the ends of the fastener for stretching it longitudinally to close the fastener, and whereby pull tabs are provided intermediate the ends to exert a cross-wise pull for opening the fastener. 40

6. The combination set forth in claim 1 wherein the projections are of substantially T-shape.

7. The combination set forth in claim 1 where- 45 in the projections and recesses are approximately triangular in shape with the wide end of the projection being farthest from the strip.

8. The combination set forth in claim 1 wherein the projections and recesses are hook shaped.

HARRY E. SIPE. 50
